UNITED STATES PATENT OFFICE.

WALTER F. SCHULZ, OF BROOKLYN, NEW YORK.

ARBURETER.

1,069,817.

Specification of Letters Patent. Patented Aug. 12, 1913.

Application filed August 21, 1911. Serial No. 645,233.

To all whom it may concern:

Be it known that I, WALTER F. SCHULZ, citizen of the United States, residing at Brooklyn, in the county of Kings and State 5 of New York, have invented certain new and useful Improvements in Carbureters, of which the following is a specification.

This invention comprehends certain new and useful improvements in carbureters for 10 internal combustion engines, and the invention has for its primary object an improved device of this character which will be sensitive, positive and accurate in its action, to properly proportion the air and gasoline or 15 other hydrocarbon according to the speed of the engine, and which will be durable in construction, and not liable to get out of order and practically indifferent to wear.

With these and other objects in view as 20 will more fully appear as the description proceeds, the invention consists in certain constructions, arrangements and combinations of the parts that I shall hereinafter fully describe and claim.

25 For a full understanding of the invention, reference is to be had to the following description and accompanying drawings, in which:

Figure 1 is a vertical sectional view of a 30 carbureter constructed in accordance with my invention; Fig. 2 is an enlarged detail side elevation of a cylinder forming part of the device; and Fig. 3 is a similar view of a plug, designed to be mounted in said cylinder and hereinafter more specifically described.

Corresponding and like parts are referred to in the following description and indicated in all the views of the drawings by the same 40 reference characters.

The casing 1 of my improved carbureter is formed with the usual throttle controlled mixture passage 2 which communicates at one end with the interior of a vertically 45 disposed cylinder 3 closed at its top by a removable screw cap 4 and containing a hollow piston 5. The piston 5 is formed with any desired number of ports 6 designed, in one position of the piston, to register 50 with ports 7 formed in the cylinder 3, and the piston is further provided with a rod 8 which extends down through the bottom wall of the casing 1 into a detachable cyl-

inder 9, a suspension spring 10 being mounted in the last named cylinder and connected 55 to the rod 8 and to the casing, so as to normally hold the piston 5 in closed position at the upper limit of its movement with the communication cut off between the ports 6 and 7. As is manifest, the ports 7 open to 60 the atmosphere.

The piston rod 8 is operatively engaged by one end of a rocking arm or lever 11 which is fulcrumed intermediate of its ends in the casing 1 within the passage 2, as at 65 12, the relatively short arm of said lever being connected to the upper end of a piston 13 in the form of a cylindrical tube open at both ends and throughout its length. The pistons 5 and 13 constitute the air admission 70 valves of the carbureter, and for the purpose of distinction I shall hereinafter refer to the piston 5 as the second or auxiliary air admission valve, and the piston 13 as the main or primary air admission valve, 75 although it is to be understood that this terminology is used only for the sake of clearness and that in reality the two valves are coördinate. The piston 13 is longitudinally movable within an open ended cylindrical valve casing 14 which is surrounded by an air admission chamber 15, the upper 80 end of which communicates with atmospheric air by the port or ports 16 formed in a downward extension of the casing 1, 85 said extension serving as the support for the float chamber 17. The chamber 17 communicates with the interior of the valve casing 14 at the lower end of the latter, by 90 means of any desired number of ports 18.

The valve casing 14 is formed with one or more ports 19, said ports being preferably in the form of parallelograms disposed obliquely as shown, and being two in number in the present instance. When the auxiliary air admission valve or piston 13 is in the lowered position, it covers the ports 19. In carrying out my invention, having particular reference to this important feature thereof, namely, the construction and arrangement of means for admitting the air and fuel at this point into the carbureter and properly mixing the same, I bore out the lower portion of the valve casing 14 up to the end of the lower longer sides of 100 105 the parallelogram ports 19, and into this

bore a plug tube 20 is inserted without changing the inner diameter of the main cylinder bore. The bottom of the plug 20 is closed, and the outer surface of the plug is formed, in that part of the exterior surface thereof which is in line with one or both of the parallelogram ports 20, with a predetermined number of vertically disposed grooves 21 which are in communication with the fuel in the float chamber 17. The upper end of the plug 20 is slotted to conform to the lines of the ports 19, as best illustrated in Fig. 3.

The construction and arrangement of the parts having been now described, I shall proceed to set forth the operation thereof.

Normally, the valves are in closed position, and both move in unison. As soon as the piston, owing to the suction of the engine, moves toward open position, the air fuel admission valve or piston 13 performs two functions. It opens, to a greater or less extent the parallelogram ports 19 and exposes to the air rushing therethrough from the ports 16 and air admission chamber 15, more and more of the vertical grooves 21 in the plug or tube 20. The superficial area of the grooves exposed is, as is obvious always in proportion to the degree of opening of the ports 19.

From the foregoing description in connection with the accompanying drawing, it will be seen that I have provided a very simple and efficient construction of carbureter which will be durable and not liable to get out of order and which will be accurate and indifferent to wear. There is no inspirator nozzle, as such, or needle valve to coat therewith and which is so liable to become worn and stick, or clogged up, and it is evident that by doing away with such elements and by providing parts which will subserve all of the functions of such parts without their incidental disadvantages, I have made a distinct advance in the art and done away with the numerous difficulties which have heretofore been experienced by all users of internal combustion engines and carbureters therefor, in the clogging of the needle valve and the consequent failure of the carbureter to feed the proper proportion of gaseous fuel and to mix the same properly with the incoming air.

Preferably the air valve 5 is axially movable to provide for adjustment, it being secured by pins, as shown, to the axially movable screw cap 4. Hence, it will be understood that by turning the screw cap, the relation of the ports in the piston and the ports in the cylinder is changed, the arcs of the port openings being lengthened or shortened. In this way, a variable movement of the air valve can be obtained for a given quantity of air, and with this a variable lift of the smaller piston that governs the fuel

flow. The extremity of the longer arm of the lever 11 is mounted on a spring-pressed pin 8^a held within the stem 8 of the air valve 5, so as to take up wear and prevent back-lash.

While the accompanying drawing shows what I believe to be the preferred embodiment of my invention, it is to be understood that the invention is not limited thereto, but that various changes may be made in the construction, arrangement and proportions of the parts without departing from the scope of the invention as defined in the appended claims.

Haying thus described the invention what is claimed as new is:—

1. A carbureter comprising a casing provided with a gasoline chamber, with a mixture outlet passage and an air inlet, a valve casing mounted in the main casing and communicating with the gasoline chamber and said passage and formed with a port communicating with the air inlet, and a movable member mounted in said valve casing and operable to open and close said port to the interior of said movable member and at the same time vary the feed of the gasoline from the gasoline chamber into said piston.

2. A carbureter, comprising a main casing provided with a gasoline chamber, with a mixture outlet and with an air inlet, an open valve casing mounted in the main casing and communicating at one end with the gasoline chamber and at its opposite end with the mixture outlet, an open-ended piston mounted in said valve casing, the latter being formed with a port exposed to the air inlet, and a plug tube mounted in said valve casing and formed in its periphery with a plurality of longitudinal grooves leading to said port.

3. A carbureter, comprising a main casing, provided with a gasoline chamber, with a mixture outlet and with an air inlet, a valve casing mounted in said main casing and formed with a port exposed to the air inlet, said valve casing communicating with the gasoline chamber and with the mixture outlet, an open piston movable in said valve casing, and means in said valve casing formed with a plurality of fuel passages leading longitudinally to the port, said means otherwise cutting off the gasoline chamber portion of said valve casing from the portion thereof which is exposed to the mixture outlet, the piston being arranged to simultaneously open varying portions of said passages and said port.

4. A carbureter, comprising a casing provided with a gasoline chamber, with a mixture outlet and with an air inlet, an open-ended valve casing having one end in open communication with the gasoline chamber and at its other end in open communication with the mixture outlet, said valve casing be-

ing formed intermediate of its ends with an obliquely disposed parallelogram port, a plug mounted in said valve casing intermediate of the ends thereof and formed with a plurality of longitudinally extending grooves leading from one end to the other thereof, the plug being cut away to conform to said port, and an open-ended piston operable in said valve casing and arranged to open and close said port and to expose greater or less portions of said grooves.

5. A carbureter, comprising a main casing, a valve casing mounted therein, a gasoline chamber communicating with one end of said valve casing, the main casing being formed with a mixture outlet communicating with the other end of said valve casing and with an air inlet, the valve casing being formed with a port, a plug mounted in said cylinder and formed in its exterior with a plurality of vertical grooves establishing communication between the two ends of the valve casing but otherwise cutting off one end thereof from the other, an open-ended piston mounted to move in said valve casing to open and close the port thereof and expose more or less of said grooves below the lower end of said piston, and a spring actuated air valve movable in the main casing and arranged to admit air into the mixture outlet, and a connection between said valve and said piston.

6. A carbureter, comprising a main casing embodying a valve casing mounted therein, the main casing being formed with a gasoline chamber communicating with one end of said valve casing and with a mixture outlet communicating with the other end of said valve casing, the valve casing being formed with a port exposed to the atmosphere, a plug mounted in said valve casing and formed in its exterior with a plurality of vertical grooves establishing communication between the two ends of said valve casing, an open-ended piston mounted to move in said valve casing to open and close the port thereof and to expose more or less of said grooves below the lower end of said piston, a spring controlled air valve mounted in the main casing and arranged to admit air into the mixture outlet, and a lever fulcrumed in said main casing and pivotally connected at its opposite ends to said valve and said piston.

55. 7. A carbureter comprising a main casing provided with a gasoline chamber, a mixture outlet passage, an air admission chamber open to the atmosphere and with air admission ports distinct from said chamber, a valve casing mounted in said air admission chamber and communicating at one end with the gasoline chamber, said valve casing being formed with a port exposed to the air chamber, a plug mounted in said valve casing and formed with a plurality

of vertical grooves establishing communication between that end of the valve casing which communicates with the gasoline chamber and said port, but otherwise cutting off one end of said valve casing from the other end, an open-ended piston movable in said valve chamber and arranged to expose more or less of said port to the grooves, a spring controlled air valve mounted in the main casing and arranged to open and close the said air admission ports, and a lever fulcrumed intermediate of its ends in the casing and operatively connected at its ends to said piston and valve.

8. The combination with a mixing chamber and a fuel chamber, of a valve casing leading from the fuel chamber to the mixing chamber and having a series of longitudinally-extending fuel channels closed at one end and opening toward the fuel chamber, the casing also having a diagonally arranged slot upon its inner face intersecting said fuel channels and a tubular valve disposed within the valve chamber and open at both ends, said valve acting to cover or uncover a greater or less portion of said slot as it is shifted to thereby control the feed of fuel from the fuel chamber to the mixing chamber.

9. The combination with a mixing chamber and a fuel chamber, of a valve casing leading from the fuel chamber to the mixing chamber, an annular plug therein having longitudinally extending channels in its circumference, said channels being open at the end of the plug directed toward the fuel chamber, said plug being formed with a diagonally arranged slot extending inward from its inner face and intersecting said channels, a tubular valve disposed within the plug and valve chamber, and means for shifting the valve to uncover a greater or less number of the said channels at the slotted opening thereof.

10. The combination with a mixing chamber and a fuel chamber, of a tubular valve casing leading from the fuel chamber to the mixing chamber, said valve casing having a diagonal slot formed therein, an annular sleeve disposed within the valve casing and having a diagonal slot registering with the diagonal slot in the casing, said plug being also formed with longitudinally extending fuel channels on its circumference, said channels being intersected by said slot, a tubular valve open at both ends and disposed within the valve casing and adapted as it is shifted to uncover a greater or less portion of the said slot in the plug, and suction operated means for shifting said valve.

11. A carbureter including a mixing chamber, a fuel chamber, a tubular valve chamber connecting the mixing chamber

with the fuel chamber and having an air inlet in its wall, means for feeding fuel from the fuel chamber to a point in the valve chamber immediately adjacent to the 5 air inlet, a sliding open ended tubular valve mounted in said valve chamber and variably opening and closing said air inlet to vary the air supply and coincidentally vary

the fuel supply, and suction operated means for shifting said valve.

In testimony whereof I affix my signature in presence of two witnesses.
